UNITED STATES PATENT OFFICE

2,033,401

COMBINATION CASE, DISPENSING MEANS,
AND TEMPERATURE RETAINING MEMBER

Martin C. Schwab, Chicago, Ill.

Application March 7, 1935, Serial No. 9,790

5 Claims. (Cl. 206—56)

Among the objects of my invention are to create a case so constructed as to have the use and functions of a packing member for holding an article such as a bottle, container, or the like in transit or storage and also for use in holding said bottle, or the like, in such a manner that its contents may be dispensed and at the same time to substantially retain a desired temperature during the dispensing operation, and such other objects, advantages and capabilities as will later more fully appear and which are inherently possessed by my invention.

Heretofore in the art it was necessary to first pack a bottle in a shipping carton or other container. When the bottle was ready for use it was withdrawn from the container and the container was thrown away. The bottle was then inserted in a dispensing member which ordinarily took the shape of an open frame, which, of course, had no heat retaining properties. If it were desired to keep the bottle at a certain temperature it was necessary for the user to place a covering around the bottle. With my structure all three of the structures formerly used are separately dispensed with because my structure operates as shipping container, holding and dispensing member and temperature retaining means. When my case has served its purpose as a shipping and storage carton it is not thrown away like the old carton but is immediately available and has utility as both a dispensing and retaining member and as a temperature retaining means. I, therefore, do with one structure what has heretofore required the use of three distinct devices.

While I have shown in the accompanying drawing a preferred form of my invention yet I wish it understood that the same is susceptible of modification and change without departing from the spirit of my invention.

Referring more particularly to the drawing, Fig. 1 is a side elevation of my case with bottle for shipment; Fig. 2 is a longitudinal cross section of my case with bottle in inverted position for dispensing; Fig. 3 is a horizontal cross section on line 3—3 of Fig. 2; Fig. 4 is a view similar to Fig. 1 showing modified window construction; and Fig. 5 is a horizontal cross section on line 5—5 of Fig. 4.

My invention more in detail comprises a case 10 preferably formed in the shape of a box having four side walls 11, 12, 13 and 14, and an open top which may be closed by the bending forward of flaps 15 and 16. Said case 10 has at its bottom 17 a cutout portion 18 smaller than the bottom 17 so that a bottle 19 or the like inserted into said

case 10 will have its bottom 20 safely resting on the bottom 17 of the case 10. After the bottle is inserted the flaps 15 and 16 may be closed and the bottle 19 shipped or stored for use. When it is desired to use the bottle 19 the flaps 15 and 16 may be opened and the bottle 19 removed. The bottle 19 may be immediately used or warmed or cooled to a desired temperature. The bottle 19 may then be placed head first into the case 10 so as to permit its neck 21 to extend through opening 18. If desired a dispensing member 22 may be fixed to the mouth of the bottle. The case 10 may be attached to a support or even to the wall of a room or the like through opening 23 in one of the walls preferably shown at 12. The bottle 15 is thus held in position for dispensing and its temperature substantially retained by the snugly surrounding walls and ends of the case 10.

I may provide my case 10 with a window 24, said window being merely a cutout portion or 20 covered with isinglass or other transparent material 25 or said opening 24 may be in the shape of a swingable door 26. Through this opening 24 may be read any gradations or numbers 27 on the bottle so that the bottle may be dispensed according to desired measurements. As an aid to the reading I may also have another cutout portion 28 preferably on the opposite wall of the case 10 to the opening 24 so as to allow light to be admitted, or I may use color on the back of the case opposite the window for purposes of increased visibility.

While my invention in its preferred form provides that the bottle or other container be shipped or stored in the case in the position shown in Fig. 1, yet it is within the spirit of my invention that the bottle or other container may be shipped or stored in a case in the position shown in Fig. 2 with the end of the case shortened to eliminate the unnecessary space.

Having thus described my invention, I claim:

1. A combination shipping and dispensing device for bottles comprising a plurality of walls, a closable top and a fixed bottom, said bottom having a cutout portion smaller in diameter than the bottom of the inserted bottle so that the bottle may be held within said case in normal upright position for shipping and storage purposes, but said cutout portion being larger in diameter than the neck of said bottle so that the bottle may later be reversed and the neck of said bottle extended through said cutout portion for dispensing the contents thereof, said case having means for attachment to a support during the dispensing operation.

2. A combination shipping and dispensing device for bottles comprising a plurality of walls, a closable top and a fixed bottom, said bottom having a cutout portion smaller in diameter than the bottom of the inserted bottle so that the bottle may be held within said case in normal upright position for shipping and storage purposes, but said cutout portion being larger in diameter than the neck of said bottle so that the bottle may later be reversed and the neck of said bottle extended through said cutout portion for dispensing the contents thereof, said case having means for attachment to a support during the dispensing operation, the temperature of said bottle and its contents being substantially retained by the protection of said casing during the dispensing operation. 5
3. A combination shipping and dispensing device for bottles comprising a plurality of walls, a closable top and a fixed bottom, said bottom having a cutout portion smaller in diameter than the bottom of the inserted bottle so that the bottle may be held within said case in normal upright position for shipping and storage purposes, but said cutout portion being larger in diameter than the neck of said bottle so that the bottle may later be reversed and the neck of said bottle extended through said cutout portion for dispensing the contents thereof, said case having means for attachment to a support during the dispensing operation, the temperature of said bottle and its contents being substantially retained by the protection of said casing during the dispensing operation. 10
4. A combination shipping and dispensing device for bottle comprising a plurality of walls, a closable top and a fixed bottom, said bottom having a cutout portion smaller in diameter than the bottom of the inserted bottle so that the bottle may be held within said case in normal upright position for shipping and storage purposes, but said cutout portion being larger in diameter than the neck of said bottle so that the bottle may later be reversed and the neck of said bottle extended through said cutout portion for dispensing the contents thereof, said case having means for attachment to a support during the dispensing operation, the temperature of said bottle and its contents being substantially retained by the protection of said casing during the dispensing operation. 15
5. A combination shipping and dispensing device for bottles comprising a plurality of walls, a closable top and a fixed bottom, said bottom having a cutout portion smaller in diameter than the bottom of the inserted bottle so that the bottle may be held within said case in normal upright position for shipping and storage purposes, but said cutout portion being larger in diameter than the neck of said bottle so that the bottle may later be reversed and the neck of said bottle extended through said cutout portion for dispensing the contents thereof, said case having means for attachment to a support during the dispensing operation, the temperature of said bottle and its contents being substantially retained by the protection of said casing during the dispensing operation, one of said walls having an opening through which may be seen the amount of contents within the bottle, and another opening in a wall opposite said first mentioned wall so as to admit light and make easier the ascertaining of the amount within the bottle. 20
6. A combination shipping and dispensing device for bottles comprising a plurality of walls, a closable top and a fixed bottom, said bottom having a cutout portion smaller in diameter than the bottom of the inserted bottle so that the bottle may be held within said case in normal upright position for shipping and storage purposes, but said cutout portion being larger in diameter than the neck of said bottle so that the bottle may later be reversed and the neck of said bottle extended through said cutout portion for dispensing the contents thereof, said case having means for attachment to a support during the dispensing operation, the temperature of said bottle and its contents being substantially retained by the protection of said casing during the dispensing operation, one of said walls having an opening closed by a transparent covering through which may be seen the amount of contents within the bottle. 25
7. A combination shipping and dispensing device for bottles comprising a plurality of walls, a closable top and a fixed bottom, said bottom having a cutout portion smaller in diameter than the bottom of the inserted bottle so that the bottle may be held within said case in normal upright position for shipping and storage purposes, but said cutout portion being larger in diameter than the neck of said bottle so that the bottle may later be reversed and the neck of said bottle extended through said cutout portion for dispensing the contents thereof, said case having means for attachment to a support during the dispensing operation, the temperature of said bottle and its contents being substantially retained by the protection of said casing during the dispensing operation, one of said walls having an opening closed by a transparent covering through which may be seen the amount of contents within the bottle. 30
8. A combination shipping and dispensing device for bottles comprising a plurality of walls, a closable top and a fixed bottom, said bottom having a cutout portion smaller in diameter than the bottom of the inserted bottle so that the bottle may be held within said case in normal upright position for shipping and storage purposes, but said cutout portion being larger in diameter than the neck of said bottle so that the bottle may later be reversed and the neck of said bottle extended through said cutout portion for dispensing the contents thereof, said case having means for attachment to a support during the dispensing operation, the temperature of said bottle and its contents being substantially retained by the protection of said casing during the dispensing operation, one of said walls having an opening closed by a transparent covering through which may be seen the amount of contents within the bottle. 35
